UNITED STATES PATENT OFFICE.

FREDERIC R. SAWYER, OF MALDEN, MASSACHUSETTS.

TWINE-REEL.

1,039,820.

Specification of Letters Patent.

Patented Oct. 1, 1912.

Application filed August 13, 1910. Serial No. 577,017.

To all whom it may concern:

Be it known that I, FREDERIC R. SAWYER, a citizen of the United States, residing in Malden, in the county of Middlesex and 5 State of Massachusetts, have invented certain new and useful Improvements in Twine-Reels, of which the following, taken in connection with the accompanying drawings, is a specification.

10 My invention relates to improvements in twine reels of the class in which a roll or spool of twine is rotatably supported in such a manner that the twine may be reeled off in the lengths required.

15 The main objects of the invention are, first, to afford improved means for frictionally controlling the rotation of the roll or spool of twine; second, to permit the use of finished and glazed twine or cord as well 20 as the unfinished variety heretofore employed, and third, to allow various sizes of rolls to be used, and to prevent the twine from becoming loose or knotted, and from escaping over the ends of the roll.

25 These with other details of the invention will be hereinafter more particularly pointed out and described, and illustrated on the accompanying drawings, in which—

Figure 1 is a side elevation of the reel with 30 a roll of twine in place thereon, and Fig. 2 is an end elevation of the same.

As illustrated in the drawing the reel comprises a support comprising a base or attaching portion 1 having screw holes 2 35 through which screws may be passed for securing the reel in any desired position. The support is in the form of a yoke having substantially parallel arms or standards 4 and 5 provided with holes 6 for receiving 40 the ends or journals 8 of the spindle 10. The spindle is provided with shoulders 12 on the inner ends of the journals against which the standards 4 and 5 are adapted to bear. The supporting member is made of 45 steel so that the arms or standards 4 are resilient and can be bent to engage the shoulders 12 with any degree of friction in order to retard the rotation of the reel and cause it to stop when the user ceases to 50 draw twine from the roll.

The twine roll 14 is provided with a central passage 15 which may be lined with a tube or not and receives the screw-threaded spindle 10. The roll is centered about the 55 spindle and held in this centered position

by flanges 16 and 18 provided with wings 20 by which these flanges may be rotated. The flanges may be formed of sheet metal and stamped to form hollow bosses 22 which are internally threaded to fit the threads on 60 the spindle 10. These flanges 16 and 18 are screwed tightly against the ends of the twine roll 14 so that the roll is maintained in a centered position upon the reel and the strand of twine is prevented from slipping 65 over the flanges to become entangled about the spindle. As the flanges 16 and 18 fit tightly against the ends of the roll the twine is prevented from being drawn down between the end of the roll and the opposing 70 flange and thus becoming caught.

From the construction above set forth it will be seen that any kind of twine may be utilized upon this reel since no matter how 75 glazed or stiff the twine may be it can not slip off of the ends of the roll as is usual in highly glazed twine. Furthermore by bending the arms or standards 4 and 5 suitably the desired degree of friction may be maintained between said standards and the 80 shoulders 12 to produce a drag or retardation upon the spindle so that the latter will not rotate under the momentum produced by drawing the twine rapidly from the reel, since the friction of the standards against 85 the shoulders 12 can be made sufficient to stop the reel substantially instantaneously after the user ceases to pull the twine.

While I have illustrated and described a preferred embodiment of the invention, I 90 am aware that many modifications can be made therein by any person skilled in the art without departing from the scope of the invention as expressed in the claims. Therefore I do not wish to be limited to all the 95 details of construction shown and described, but

What I claim is—

1. A twine reel, comprising a screw-threaded spindle having a shoulder near 100 each end, a pair of flanges having tapped hubs mounted on said spindle, said flanges having wings on their outer faces for rotating them and having plane inner faces to engage substantially the entire end faces of 105 a tube of twine, whereby the reel is adapted to hold various sizes of tubes of twine, and the twine, in unreeling, is prevented from catching between the ends of the tube and said flanges, and means for frictionally 110

engaging the shoulders on said spindle to arrest the rotation of said reel when the user ceases to pull the twine.

2. A twine reel, comprising a U-shaped standard, the arms of which are resilient and are provided with aligned apertures, a screw threaded spindle having its end portions journaled in said apertures and provided with shoulders which are frictionally engaged by the resilient arms of the standard, and a pair of flanges each having a screw threaded hub and means on its outer face for rotating the same to adjust said flanges toward and away from each other, whereby tubes of twine of various lengths

and diameters can be centered and securely clamped between said flanges to prevent the twine, in unreeling, from catching between the ends of the tube and the flanges, the frictional engagement of the standard with 20 said shoulders causing the reel to cease rotating when the user ceases to pull the twine.

In testimony whereof I have signed my name to this specification in the presence of two subscribing witnesses.

FREDERIC R. SAWYER.
